12 Claims. (Cl. 28—21)

This invention, in general, relates to machinery for packaging textile ribbons and similar ribbon-like articles in parallelepiped receptacles such as cartons, boxes and the like. More particularly, the invention relates to packaging machinery in which ribbon-like articles are packaged in layers without twist to the ribbon-like article.

During the manufacture of filaments or fibers, the filaments or fibers are often in the form of a ribbon or composed of many filaments or fibers. This ribbon form is a transitional intermediate between the initial spinning or processing stage for the fibers or filaments and the final processing therefrom in the form of textiles or other ultimate products. It is often desirable to pack these ribbons in cartons for shipment to a textile manufacturer or the like.

One known method for packaging textile ribbons is to employ distributing funnels into which is pumped compressed air. The thread and ribbon form is introduced into the distributing funnels and moved by the air flowing through the funnels. For packaging, the exit end of the distributing funnels are moved in a controlled pattern immediately above a stationary receptacle position underneath in order to lay the ribbons in layers. This type of packaging device has not proven to be satisfactory because it is not possible to fill the entire volume in the parallelepiped receptacle—particularly along the inside walls thereof. The empty spaces left in the receptacle permitted shifting of the ribbons and led to tangling thereof during shipment of the receptacles. Also, the swinging distributing funnel had another disadvantage in that it required a considerable structural height—making accessibility and maintenance of the installation difficult.

Textile ribbon packaging machinery has also been proposed wherein the receptacles are mounted on eccentrically-mounted, rotating plates. By means of parallel guides, these packaging machines distribute the textile ribbons in a circular manner without imparting twist thereto. While these packaging machines provided some improvements in the packaging of textile ribbons, they were nonetheless unsuitable for depositing the textile ribbons in parallelepiped receptacles in horizontal layers. For example, delicate ribbons, such as ribbons of torn, untwisted, crimped fibers became so entangled in the receptacle that they could not be subsequently drawn out of the receptacle and immediately used as slubbing. It would be of considerable advantage to be able to draw the packaged ribbons from the container and immediately use the ribbon, because it would save the processor of the fibers a renewed run through spinning mill preparation machines before feeding the ribbon to spinning machines.

This invention is primarily directed to improvements in machinery for packaging textile ribbons and the like in parallelepiped receptacles by distributing the ribbons during the packaging operation in a plurality of superposed, horizontal rows. In accordance with the invention, the ribbons are packaged so as to fill substantially entirely the volume of the receptacle and thereby pre-

2

vent shifting of the ribbons with ensuing tangling during shipment and further handling of the packaged article.

To achieve this and other objectives of the invention, the textile ribbon packaging machine comprises the combination of a pair of cooperating feed rollers positioned above the parallelepiped receptacle. The receptacle rests on a platform which is reciprocated in one direction, while simultaneously being reciprocated at a slower rate in a direction at right angles to the first mentioned direction of reciprocation. Stated in an alternative manner, the frequency of reciprocation in one direction is a multiple of or many times the frequency in the other direction. This motion provides a laying of the continuously fed ribbon in horizontal rows with a zigzag pattern. By adjusting the reciprocal movement imparted to the receptacle in each direction in accordance with the structural dimensions of the receptacle and the width of the ribbon, the receptacle can be filled substantially completely and compactly with the textile ribbon so as to prevent subsequent entanglement of the ribbon resulting from shifting thereof in the receptacle.

One means for achieving this result is to mount the platform for the receptacle for reciprocal movement relative to an intermediate support. The intermediate support is, in turn, mounted upon a base support for reciprocal movement relative to the base support in a direction at right angles to the reciprocal movement of the platform relative to the intermediate support. The frequency of reciprocation in one direction is considerably greater than in the other direction so that the ribbon is laid in horizontal rows across the width of the box, each horizontal row being in a zigzag pattern.

A specific embodiment of a packaging machine contemplated by our invention is illustrated in the drawing 35 wherein:

Fig. 1 is a side elevation in cross-section of the embodiment;

Fig. 2 is a top plan view of the embodiment; and

Fig. 3 is a cross-sectional view taken along section 40 3—3 of Fig. 1.

Referring to the drawing, the thread ribbon R is fed to the packaging machine by means of a pair of cooperating, rotatably-driven drive rollers 1, 2. These drive rollers are positioned above a parallelepiped receptacle 3, in this case a cardboard carton of conventional construction, 45 by positioning the carton directly under the rollers on a carton-supporting platform composed of rollers 4 rotatably journaled in end bearing supports 5. The platform is further composed of an open frame 6 having rectangular side panels 7—the bearing supports 5 being mounted on said side panels 7. The receptacle 3 remains stationary with respect to its support platform during a given packaging operation and, if necessary, a frictional drag for each of the rollers 4 may be used to prevent accidental shifting of the receptacle 3 on the rollers 4 50 during the packaging operation. The major purpose of the rollers 4 is to facilitate the initial installation and removal of the carton at the beginning and end of the packaging operation.

The carton supporting platform is mounted for reciprocal movement in one direction with respect to an intermediate support, designated generally at 10 in the drawing, by mounting the lower edges of the straight side panel 7 of the open frame 6 in freely rotatable, aligned, peripherally grooved rollers 8 rotatably-mounted in supports 9 on the intermediate support 10.

The drive for reciprocating the frame 6 with respect to the intermediate support 10 is achieved by providing a cross bar 11 extending between the side panel 7 of the frame 6. The cross bar 11 has an enclosed slot 12 into which extends the shaft of a bolt 13, the bolt, in turn, being secured by means of lock nut 14 to a rocker

arm 15. The rocker arm 15 is pivotally mounted at 16 on a bracket 17 of the intermediate support 10. The shaft of the bolt 13, riding in the slot 12, imparts a linear motion to the frame 6 along the rollers 8 when the rocker arm 15 is pivoted. By oscillating the arm 15, reciprocal motion is imparted to the frame 6 and, hence, to the carton 3 supported thereon. A pivoted position of the arm 15 is illustrated at 15' in Fig. 2.

To impart oscillating motion to the arm 15, there is provided a drive composed of a pin 19, which rides in a slot 18 at the end of the arm 15. The pin 19 extends upwardly from the top of a U-shaped, motion transfer fork 20, whose legs form a slot 21 extending vertically between the upper and lower flights of a pair of chain drives 22, 23. These chain drives 22 and 23 are identical and are positioned in side by side relationship. Each chain drive is supported on a sprocket 24 mounted for free rotation on support 26 at one end and on the other end by drive sprocket 25 mounted for rotation on support 27. The two chains 22 and 23 have extending therebetween a cylindrical rod 28, which rides in the slot 21 of the motion transfer fork 20. As the chains move the rod 28 in one direction along the upper flight of the chains and in the other direction along the lower flight of the chains, the rod 28 imparts a reciprocating motion to the transfer fork 20, which, in turn, oscillates the rocker arm 15 by means of the connection of the latter with the motion transfer fork 20 through slot 18 and pin 19. The drive position of the rod 28 when it is on the lower flight of the pin drive is shown in phantom at 28' in Fig. 1.

In order to accommodate the packaging machine for filling receptacles of various dimensions, the amount of reciprocal movement imparted to the frame 6 can be adjusted by positioning the bolt 13 at various points in the slot 12 of the cross bar 11. As the bolt 13 is moved toward the pivot 16 the length of the reciprocal motion imparted by the fixed oscillating pattern of the rocker arm 15 becomes less. It becomes greater as the bolt 13 is positioned in the slot 12 at greater distances from the pivot 16. The details of one means for adjustably positioning the bolt 13 on the rocker arm 15 will be described later with respect to a similar rocker arm 66, this description being equally applicable to the rocker arm 15.

The chains 22 and 23 are driven by a motor 29, whose rotating shaft is connected with the drive sprockets 25 by means of a V-belt 32 drivingly connecting cone pulleys 30 and 31. These cone pulleys have a plurality of grooves of different diameter for providing a variable speed drive in accordance with the positioning of the V-belt 32. These variable speed drives are further means for varying the frequency of reciprocal movement of the frame 6. Other equivalent drives, such as variable speed gear drives may be substituted for the V-belt drives illustrated.

The pulley 31 has a direct drive connection with one of the sprockets 25. However, inasmuch as the space between the sprockets 25 must be left free to permit movement of the motion transfer fork 20 therebetween, it is not possible to connect the other sprocket 25 by an axial shaft extending thereto. Accordingly, the drive from the pulley 31 to the sprocket 25, remote therefrom, is achieved by a spur gear drive, including a connecting shaft 33 extending between the chains at a position lower than the lower edge of the motion transfer fork 20. The gear drive will be described in later detail with respect to sprockets 50 and 57. The gear mechanism in the drive arrangement between the pulley 31 and the sprocket 25, remote therefrom, is designated generally at 38 and 39. This description is equally applicable to the drive connection between the two sprockets 25 with the pulley 31.

Up to this point there has been described a unit which will impart reciprocal motion in one direction to a receptacle 3 mounted on a support platform. However, in order to lay the ribbons in horizontal rows, it is necessary to provide a reciprocal motion to the receptacle 3

in a direction at right angles to the reciprocal motion imparted by the mechanism heretofore described. One way of achieving this function is to construct the intermediate support unit 10 of a base plate 34 having side walls 35 and a partial top wall 36, having therein an opening 37. This structure forms a housing for the chain drive and power connections therefor and enables the whole unit, including the receptacle supporting platform composed of the rollers 4 and frame 6, to be reciprocated in a direction perpendicular to the reciprocal motion of the frame 6.

The reciprocal motion of the intermediate support 10 is accomplished by providing aligned rollers 40 on the bottom surface of the base plate 34. These rollers ride in parallel, linear grooves 41 provided in the upper surface of inwardly turned flanges 42 and 43 of the hollow base support 44.

A power drive is employed to reciprocate the intermediate support 10 on its rollers 40 by an electric motor 45. The drive shaft of the motor 45 drives a cone pulley 46, which, in turn, drives the cone pulley 47 via the V-belt drive 48. The V-belt 48 and cone pulleys 46 and 47 provide a variable speed drive for driving sprockets 50 and 57. The sprocket 50 is rotatably driven by the pulley 47 by means of a direct drive shaft 49. However, it is not possible to extend the drive shaft 49 between the sprockets 50 and 57 because this shaft would then interfere with movement of the U-shaped motion transfer fork 63. The drive for the sprocket 57, accordingly, is constructed to avoid interference with movement of the motion transfer fork 63 by mounting on the shaft 49 a spur gear 51, which, in turn, drives spur gear 52. The drive imparted to spur gear 52 is transmitted to spur gear 54 by connecting drive shaft 53 positioned lower than the lower end of the motion transfer fork 63. Spur gear 54, in turn, drives spur gear 55 at a rate of revolution equal with the rate of revolution of the spur gear 51—the gears 51, 55 and 52, 54, respectively, being identical. The spur gear 55 rotates the sprocket 57 at a rate of revolution equal with the rate of rotation of the sprocket 50 via connecting drive shaft 56.

Sprockets 51 and 57 drive parallel chains 58 and 59, respectively—each chain passing over a freely rotatable sprocket of identical construction with the sprocket 24. The chains 58 and 59 travel at an equal velocity. The gears 51, 52 and shaft 49 are rotatably journaled in a gear housing 60 and the gears 54, 55 and shaft 56 are rotatably journaled in a gear housing 61.

The chains 58 and 59 are employed to reciprocate a U-shaped motion transfer fork 63, which rides on a pin 62 extending between chains 58, 59. The operation of the motion transfer fork 63 is identical with the operation of motion transfer fork 20. The motion transfer fork 63 has extending from its upper surface a pin 64, which rides in slot 65 of a rocker arm 66, which is pivoted at 70 on bracket 71 inside the support base 44. By this construction, the to and fro movement of the pin 62 imparts an oscillating movement to the rocker arm 66. An extreme position of oscillation is shown in Fig. 3 in phantom at 66'.

The oscillating motion of the rocker arm 66 is translated into linear, reciprocal motion of the intermediate support 10 by a sliding connection of the shaft 68 of bolt 67 in an elongated slot 69 provided in the base plate 34. The shaft 68 of the bolt presses against the side walls of the slot as the arm 66 oscillates and thereby imparts a linear, reciprocal motion to the intermediate support 10.

Inasmuch as the length of reciprocal movement of the intermediate support 10 and corresponding reciprocal movement of the receptacle 3 must be varied in accordance with the inner dimension of the container 3, means is provided to vary the amount of reciprocal travel imparted to the intermediate support 10. This function is accomplished by making the bolt 67 removable and providing means for positioning this bolt at various points

along the length of the rocker arm 66. One of the ways of providing this function is to secure the bolt 67 to the rocker arm 66 by means of a nut 72—the bolt extending through an aperture 73 in the rocker arm 66. By providing a plurality of holes 73 along the length of the rocker arm 66, the bolt 67 may be positioned at variable points along the rocker arm 66 to change the length of reciprocal movement imparted by the oscillation of the rocker arm 66. As the bolt 67 is mounted in holes closer to the pivot 70, the length of reciprocal travel imparted to the intermediate support 10 will become less, and vice versa.

Thus, by providing variable speed drives between the motor and chains in the intermediate support 10 and the base support 44 and also by providing adjustment in the length of reciprocal movement imparted to the frame 6 and the intermediate support 10 by rocker arms 15 and 66, respectively, the packaging machines of the instant invention can be adjusted to accommodate the packaging of various widths of ribbons in parallelepiped containers or receptacles of various rectangular cross-sections. By selection of the proper drive speed for the chains and the proper position of the bolts on the rocker arms, the receptacle can be substantially completely filled, without void spaces along the edges, by the continuous ribbon laid in the container in a plurality of horizontal, convoluted rows 75, each row 75 containing juxtaposed segments of the ribbon R placed in said rows in zig-zag fashion.

When the container 3 is filled with the ribbon to the desired height, the next container 76 (shown in phantom) is placed on the rollers 4 and pushed underneath the feed rollers 1, 2 in place of the receptacle 3. By displacing the container 3 with the following container 76, the packaging is continued in the container 76 without interruption of the feed of the ribbon. The ribbon in the two containers is then separated by severing at a convenient point.

It will be obvious to those skilled in the art that other modifications of the generic invention herein disclosed may be made without departing from the spirit and scope thereof. For example, a single drive motor may be employed to perform the drive functions of the separate motors 29 and 45 shown in the embodiment in the drawing, this drive being connected with the chain sprockets by variable speed drives from a common shaft driven by said motor. These variable speed drives may take the form of pulley drives or may be adjustable speed gear drives. The further qualification of such drives from a common motor is the provision of a slideable drive connection or a flexible drive connection, which will permit relative movement of the intermediate support 10 with respect to the base support 44. Also, in place of the chain drives and connecting linkage for translating motion of the chain drives into reciprocal movement of the platform and the intermediate support, there may be used double pitch worm gears which drive a follower connected with the platform and/or the intermediate support for imparting reciprocal movement thereto. The double pitch followers have a left hand and right hand thread, well known in the art, which automatically reverses the direction of the travel of the follower at each end of the double pitch thread. Also, a single pitch worm gear drive may be used, which worm gear drive is driven by a reversible electric motor. This combination would include switch means for reversing the poles of the reversible electric motors at predetermined points of travel of the platform with respect to the intermediate support and/or the travel of the intermediate support with respect to the base support. Other modifications will occur to those skilled in the art for carrying out the basic objective of the invention, the reciprocal movement of the supporting platform in two directions at right angles to each other in accordance with a predetermined control pattern whereby the ribbon article is laid in the parallelepiped receptacle in tightly packed, horizontal layers.

The invention is hereby claimed as follows:

1. In a machine for packaging articles in the form of a ribbon in parallelepiped receptacles, a platform adapted to support a receptacle to be filled with an article in the form of a ribbon, means for reciprocating said platform in a linear direction of travel, additional means for reciprocating said platform in another linear direction of travel at right angles to the first-mentioned direction of travel and stationarily-positioned roller means above said platform for feeding said article to a receptacle supported on said platform during reciprocation thereof, one of said means for reciprocating being operable at a frequency of reciprocation which is a multiple of the frequency of reciprocation at which the other means for reciprocation is operable.
2. In a machine for packaging articles in the form of a ribbon in parallelepiped receptacles, a platform adapted to support a receptacle to be filled with an article in the form of a ribbon, an intermediate support, means for mounting said platform for reciprocal movement on said intermediate support, drive means for reciprocating said platform with respect to said intermediate support, a base support, means for mounting said intermediate support on said base support for reciprocal movement of said intermediate support with respect to said base support in a linear direction at right angles to the relative reciprocal movement of said platform with respect to said intermediate support, drive means for reciprocating said intermediate support with respect to said base support, and stationarily-positioned roller means above said platform for feeding said article to a receptacle positioned on said platform, one of said drive means being operable at a frequency of reciprocation which is a multiple of the frequency of reciprocation at which the other drive means is operable.
3. The packaging machine of claim 2 wherein each of said drive means includes a driven chain having substantially flat flights, means attached to said chain at a given point thereon for travel with said chain, and motion transfer means cooperating with said last-mentioned means for translating the movement of said last-mentioned means in the path of chain travel into a reciprocal drive for said platform and said intermediate support, respectively, of the machine.
4. The packaging machine of claim 2 wherein each of said drive means includes a pair of parallel, driven chains having substantially flat upper and lower flights, a pin attached to and extending between said parallel chains, and means for translating the motion of said pin during drive of said chains into a reciprocal drive for said platform and said intermediate support, respectively.
5. In a machine for packaging articles in the form of a ribbon in parallelepiped receptacles, a platform adapted to support a receptacle to be filled with an article in the form of a ribbon, an intermediate support, means for mounting said platform for reciprocal movement on said intermediate support, an oscillating rocker arm below said platform, drive means for oscillating said rocker arm, connecting means between said rocker arm and said platform for translating the oscillating movement of said rocker arm to linear drive for said platform by said rocker arm, a base support, means for mounting said intermediate support on said base support for reciprocal movement of said intermediate support with respect to said base support in a linear direction at right angles to the relative reciprocal movement of said platform with respect to said intermediate support, drive means for reciprocating said intermediate support with respect to said base support at a frequency of reciprocation which is a fraction of the frequency of oscillation of said rocker arm, and stationarily-positioned roller means above said platform for feeding said article to a receptacle positioned on said platform.
6. In a machine for packaging articles in the form of a ribbon in parallelepiped receptacles, a platform adapted

to support a receptacle to be filled with an article in the form of a ribbon, an intermediate support, means for mounting said platform for reciprocal movement on said intermediate support, drive means for reciprocating said platform with respect to said intermediate support, a base support, means for mounting said intermediate support on said base support for reciprocal movement of said intermediate support with respect to said base support in a linear direction at right angles to the relative reciprocal movement of said platform with respect to said intermediate support, an oscillating rocker arm below said intermediate support, drive means for oscillating said rocker arm at a frequency of oscillation which is a fraction of the frequency of reciprocation at which said drive means is operable, connecting means for translating the oscillating movement of said rocker arm to linear reciprocating drive for said intermediate support by said oscillating rocker arm, and stationarily positioned roller means above said platform for feeding said article to a receptacle positioned on said platform.

7. The machine of claim 5 wherein the drive means for said oscillating rocker arm comprises a driven chain having substantially flat upper and lower flights, means attached to said chain at a given point thereon for travel with said chain, and a motion transfer fork cooperating with said last-mentioned means for translating the movement of said last-mentioned means in the path of chain travel into an oscillating drive motion of said rocker arm.

8. The machine of claim 6 wherein the drive means for said oscillating rocker arm comprises a driven chain having substantially flat upper and lower flights, means attached to said chain at a given point thereon for travel with said chain, and a motion transfer fork cooperating with said last-mentioned means for translating the movement of said last-mentioned means in the path of chain travel into an oscillating drive motion of said rocker arm.

9. In a machine for packaging articles in the form of a ribbon in parallelepiped receptacles, a platform having a frame on which is supported a plurality of rollers lying in a horizontal plane, said rollers adapted to support a receptacle to be filled with an article in the form of a ribbon, means for reciprocating said platform in a linear direction of travel, additional means for reciprocating said platform in another linear direction of travel at right angles to the first-mentioned direction of travel at a frequency of reciprocation which is a multiple of the frequency of reciprocation at which said first-mentioned means is operable and stationarily-positioned roller means above said platform for feeding said article to a receptacle supported on said platform during reciprocation thereof.

10. In a machine for packaging articles in the form of a ribbon in parallelepiped receptacles, a platform having a frame on which is supported a plurality of rollers lying in a horizontal plane, said rollers adapted to support a receptacle to be filled with an article in the form of a ribbon, an intermediate support, means for mounting said platform for reciprocal movement on said intermediate

5 support, drive means for reciprocating said platform with respect to said intermediate support, a base support, means for mounting said intermediate support on said base support for reciprocal movement of said intermediate support with respect to said base support in a linear direction at right angles to the relative reciprocal movement of said platform with respect to said intermediate support, drive means for reciprocating said intermediate support with respect to said base support, and stationarily-positioned roller means above said platform for feeding said article to a receptacle positioned on said platform, one of said drive means being operable at a frequency of reciprocation which is a multiple of the frequency of reciprocation at which the other drive means is operable.

11. In a machine for packaging articles in the form of a ribbon in parallelepiped receptacles, a platform adapted to support a receptacle to be filled with an article in the form of a ribbon, means for reciprocating said platform in a linear direction of travel, additional means for reciprocating said platform in another linear direction of travel at right angles to the first-mentioned direction of travel, one of said means for reciprocating being operable at a frequency of reciprocation which is a multiple of the frequency of reciprocation for which the other means of reciprocating is operable, and stationarily-positioned feed means above said platform for feeding in a substantially constant vertical path an article in the form of a ribbon into a container supported on said reciprocable platform.

12. In a machine for packaging articles in the form of a ribbon in parallelepiped receptacles, a platform adapted to support a receptacle to be filled with an article in the form of a ribbon, an intermediate support, means for mounting said platform for reciprocal movement on said intermediate support, drive means for reciprocating said platform with respect to said intermediate support, a base support, means for mounting said intermediate support on said base support for reciprocal movement of said intermediate support with respect to said base support, in a linear direction at right angles to the relative reciprocal movement of said platform with respect to said intermediate support, drive means for reciprocating said intermediate support with respect to said base support, one of said drive means being operable at a frequency of reciprocation many times the frequency of reciprocation at which the other drive means is operable, and stationarily-positioned feed means above said platform for feeding in a substantially constant vertical path an article in the form of a ribbon into a container supported on said reciprocable platform.
